UNITED STATES PATENT OFFICE.

CLAUDE D. GROVE, OF COLORADO SPRINGS, COLORADO.

BARREL-FILTER.

SPECIFICATION forming part of Letters Patent No. 736,597, dated August 18, 1903.

Application filed January 6, 1903. Serial No. 138,062. (No model.)

To all whom it may concern:

Be it known that I, CLAUDE D. GROVE, a citizen of the United States, and a resident of Colorado Springs, in the county of El Paso and State of Colorado, have invented a new and Improved Barrel Strainer or Filter, of which the following is a description.

My invention relates to barrel strainers or filters used in straining or filtering solutions of the precious metals obtained in the treatment of ore by chemical processes, such as bromination or chlorination; and it consists of certain novel parts and combinations of parts particularly pointed out in the claims concluding this specification.

In the accompanying drawings I have shown my invention embodied in the form which is at present preferred by me; but it will be understood that various modifications and changes may be made in the structure without departing from the spirit of my invention and without exceeding the scope of my claims.

In the accompanying drawings, Figure 1 is a longitudinal view of a tank or barrel containing a filter embodying my invention, the same being partly in section and partly in elevation. Fig. 2 is a top view of a portion of the strainer-bed. Fig. 3 is a section through Fig. 2 on the line 3-3. Fig. 4 is a section through Fig. 2 on the line 4-4, Fig. 5, is a section through Fig. 2 on the line 5-5.

Similar reference-numerals in the several figures refer to the same or corresponding parts.

The following is a description of the structure illustrated in the said drawings.

5 is a cylindrical tank or barrel, preferably composed of an iron shell 6, interiorly coated with a lead sheath 7 to resist the action of the chemicals used therein.

8 are trunnions adapted to be mounted in suitable journals and to be provided with suitable means for revolving the barrel in the usual way when charged.

9 is a manhole provided with a suitable cover 10.

11 is an inlet-pipe controlled by a valve 12. 13 is an outlet valve controlled by a valve 14. 50 Within the barrel and at the bottom thereof is located my improved strainer. In the form shown in the drawings it is composed of a series of longitudinal planks or strips

15 15 15 15, (although they may be disposed transversely,) mortised at 16 16 16 to make a 55 water-tight joint between them. Instead of mortises between the planks gaskets, of asbestos or other suitable acid-resisting material, may be employed to maintain a tight joint. These planks are preferably made of wood, 60 but they may be made of any other light acid-resisting material and, on the sides adjacent to the shell of the barrel rest upon and are supported thereby and are preferably made to conform to a greater or less extent with the interior contour thereof or at least to be in contact therewith at a sufficient number of points to afford adequate means of support. On their upper sides they need not be so shaped. The planks 15 are attached to the barrel by means of bolts 19^a, passing through the planks and through the outside shell of the barrel, by means of which they are securely attached to the shell. The heads of the bolts 19^a are provided with caps 20^a, of some metal or material, such as lead, not acted upon by the chemicals used in the barrel, and suitable washers (not shown) are employed to afford 70 a tight joint to prevent leakage and to prevent the chemicals gaining access to the shaft of the bolt. Each of these planks 15 is perforated by a series of holes or slits 17. These holes or slits may be in any desired form or arrangement. In the drawings I have 75 shown them as longitudinal slits; but they might be formed in any other desired direction or the perforations might be made up of holes instead of slits. Preferably these holes or slits are made of expanding area from the 80 interior outwardly, as shown in Fig. 5, in order that any solid matter entering from the barrel may readily pass through and be discharged from them, thus preventing clogging. 85 18 represents transverse channels registering with each other and extending from the outermost perforation 17 inwardly. 90 19 is a longitudinal main channel with which the lateral channels 18 communicate. 95 20 represents grooves formed in the upper surfaces of the outside planks, by means of which fluid which would be retained at the outside edges of the planks is drained off and discharged through the perforations 17 in a manner which will be readily understood. 100 The planks may be treated with any suit-

able material or solution to resist the action of the chemicals employed. For example, they may be treated with any tarry, oily, or waxy matter, such as coal-tar, linseed-oil, or paraffin. For further reducing the chemical action and abrasion on the top of the filter the planks may be coated with a lead sheath 21, as shown in Fig. 4. By boring dovetail holes or grooves at the outer surface of the planks and then pouring melted lead or other acid-resisting metal over the top the planks will be coated with a sheath of metal held in place by lugs which fill the dovetail holes or grooves. This sheet of lead is then sawed 25 through at the slots or punched through at the holes, as will be readily understood, or staples or similar contrivances may be driven into the frame and the sheath of lead cast around and over them, thus securing the lead. 30 In operation the ore to be treated having been suitably crushed or pulverized is introduced into the barrel or cylinder through the manhole 9. Water and chemicals are then added. The tank is then revolved a sufficient 35 time for the chemicals to carry the precious metal into solution, when the motion of the cylinder is arrested with the filter at the bottom, as shown in Fig. 1. The solid contents of the barrel then settle onto the filter-bed, 40 the largest and heaviest particles settling first on top of the filtering-bed. The holes or slits 17 are small enough to prevent this material passing through them. The inlet 11 now being connected with a water-supply under pressure, the cock 12 is opened, as is also the cock 14, the outlet 13 being connected with a discharge-pipe. The process of straining or filtering under pressure then continues in the ordinary way until all the precious 45 metal in solution is removed from the tank. It will be observed that the solution passing through the holes or slits 17 gains access to the transverse channels 18 and is by them conducted to the main longitudinal channel 19, which is connected with the discharge-pipe 13 and which channel is of sufficient size to carry off all solution which will pass through the perforations 17.

The filter I have described, and illustrated 50 in the drawings, may be cheaply made, is extremely durable, is light in weight, and does not disturb the balance of the tank in rotation, occupies small space, and in this sense increases the capacity of the barrel, and being 55 securely held in place by bolts is not liable to work loose or to get out of order during operation. Furthermore, the size of the filter-bed may easily be regulated (enlarged or diminished) to control the rate of filtering by the addition or subtraction of the planks 15.

Having thus described my invention in the form which I at present prefer, what I claim, and desire to secure by Letters Patent, is— 60 1. In a barrel-strainer the combination with 65 the shell thereof, of a strainer the exterior surface of which is in contact with the barrel, its

inner surface being provided with suitable straining-perforations in the form of slits combined with transverse grooves beneath the interior surface and establishing communication between said slits and the discharge-opening. 70

2. In a barrel-strainer the combination with the shell thereof, of a strainer composed of a body having suitable straining-perforations and beneath its surface projections forming channels communicating with the discharge-opening, the straining-perforations extending entirely through said projections. 75

3. In a barrel-strainer the combination with the shell thereof, of a strainer composed of a body having suitable straining-perforations and beneath its surface projections integral therewith and forming channels communicating with the discharge-opening, the straining-perforations extending entirely through said projections. 80

4. In a barrel-strainer the combination with the shell thereof, of a strainer having suitable straining-perforations and beneath its surface projections forming channels communicating with the discharge-opening, the straining-perforations being of expanding section and extending entirely through said projections. 85

5. In a barrel-strainer the combination with the shell thereof, of a strainer composed of a body of wood and a perforated coating of acid-resisting metal directly attached thereto by dowels, rivets, or equivalent means. 90

6. In a barrel-strainer the combination with the shell thereof, of a strainer composed of a perforated body of wood, and a perforated coating of acid-resisting metal directly attached thereto by dowels, rivets or equivalent means, the perforations in the body registering with those in the metal coating. 95

7. In a barrel-strainer the combination with the shell thereof, of a sheet of acid-resisting metal provided with straining-perforations, and a support therefor containing similar perforations registering with the perforations in the metal sheet. 100

8. In a barrel-strainer, the combination with the shell thereof, of a strainer composed of a body of wood or other light material containing suitable straining-perforations, which body is supported directly by and is attached to the said shell. 115

9. In a barrel-strainer, the combination with the shell thereof, of a strainer composed of a body of wood or other light material coated with a sheath of acid-resisting material, said body containing suitable straining-perforations and being supported directly by and attached to said shell. 120

In testimony whereof I have signed my name to this specification in the presence of two subscribing witnesses.

CLAUDE D. GROVE.
